UNITED STATES PATENT OFFICE.

SAMUEL W. BATEMAN, OF EL DORADO, ARKANSAS.

SAND TRAP FOR OIL-WELL PUMPS.

Application filed April 7, 1922. Serial No. 550,553.

To all whom it may concern:

Be it known that I, SAMUEL W. BATEMAN, a citizen of the United States, residing at El Dorado, in the county of Union and State 5 of Arkansas, have invented certain new and useful Improvements in a Sand Trap for Oil-Well Pumps, of which the following is the specification.

This invention has relation to certain new 10 and useful improvements in an oil well pump structure and relates more particularly to a sand trap for the oil pump.

The invention has for an object the provision of a sand trap which may be incorporated 15 in an oil pump structure of conventional form without material alterations thereof and yet which will serve to arrest movement of the sand and other foreign matter with the oil fluid being extracted 20 from the well.

Another object of the invention resides in the provision of a sand trap of the character stated which will be of simple and efficient construction and operation and which 25 will permit the arrested sand and other foreign matter to be effectually separated from the fluid on the upward stroke of the pump sucker rod and will then pass downwardly by gravitation and return to the well on the 30 downward or return stroke of the pump sucker rod.

The invention has for a further object the provision of a sand trap of the character stated which may be included in pipe sections 35 connecting with the pump sucker rod pipe and depending therefrom, all of these pipes being inclosed in the pump casing and suitably spaced from the inner wall thereof.

A still further object of the invention resides 40 in the provision of a sand trap or separator for an oil pump which will be constructed and arranged in such a manner as to prevent filling up or clogging the same by the separated or arrested sand and other 45 foreign matter, thereby eliminating the necessity of stopping operation of the pump frequently to remove the sand and other foreign matter from the trap.

The invention has for still another object 50 the provision of a sand trap or separator of the character stated which will be of simple and inexpensive construction, composed of the minimum number of parts and which will be automatic in its operation and

which will effectively accomplish the purpose for which it is intended.

With the foregoing and other objects in view, as will appear as the description proceeds, the invention consists in the novel construction, combination and arrangement 60 of co-operating elements as hereinafter more specifically set forth, claimed and shown in the accompanying drawings forming a part of the present application and in which:—

Fig. 1 is a vertical section through a portion of an oil pump structure with the improved sand trap or separator incorporated therein.

Fig. 2 is a view similar to Fig. 1 on an enlarged scale and taken only through the sand trap or separator structure and the portion of the well casing inclosing the same.

Referring more in detail to the drawings in which similar reference characters designate corresponding parts throughout the several views, 1 indicates the well casing, 2 the pump sucker rod working in the pump pipe or barrel 3 and having the sucker rod valve structure 4 of conventional type on the lower end of the sucker rod 2. It is to be understood that the pump pipe or sucker rod inclosing barrel 3 is suitably spaced from the inner wall of the pump casing 1, as shown in the drawings. A second pump pipe or barrel 5 in alignment with the pipe 85 or barrel 3 is positioned in the lower portion casing 1 and between the pipes 3 and 5 is located the sand trap or separator structure, as will now be described in detail.

The sand trap or separator structure includes an upper pipe section 6, a lower pipe section 7 by a coupling 8 or the like, and a perforated pipe section 9 depending from the lower pipe section 7 and connected therewith by a coupling 10. The lower end of the 95 perforated section 9 is connected with the pump pipe or barrel 5 by a coupling 11. A similar coupling 12 is employed to connect the upper end of the upper pipe section 6 with the pump pipe or barrel 3. It is also to be noted that an outer perforated pipe section 13 is secured around and spaced from the perforated pipe section 9, the upper end of the perforated pipe section 13 being threaded on the coupling 10 while the lower end of the perforated pipe section 13 is contracted or reduced in diameter and threaded on the lower end portion of the perforated 100 105

pipe section 9. It is also to be noted that the pipe section 9 is perforated at its upper portion while the perforated section 13 has its perforations extending around the lower portions thereof. This structure may be readily seen by referring to the drawings.

Threaded in the upper end of the pipe section 7 is a fluid guide member 14 of substantially the form of an inverted frusto-conical member having a central passage 15 for the fluid. A small sleeve 16 is threaded in the upper end portion of the member 14 and has its bore corresponding to and registering with the central bore 15 of the member 14. A tube 17 has an enlarged lower end threaded on and inclosing the upperstanding portion of the sleeve 16. The central bore of the tube 17 also corresponds to and registers with the bore of the sleeve 16.

20 A valve seat 18 is formed on the upper end of the tube 17 and the ball valve 19 normally rests on the valve seat 18. An open valve cage 20 is threaded on the upper end of the tube 17 to inclose the ball valve 19 and limit movement of the latter when off of the valve seat 18. It will be understood that all of the parts mounted on the sleeve 16 are inclosed in the upper pipe section 6, as shown in the drawing.

30 Threaded in the lower end of the pipe section 7 is a funnel member 21 having its central passage flared at its upper end, as shown clearly in Fig. 2 to permit sand and other foreign matter to readily enter the member 21 from above the same and pass downwardly through the sleeve 22 and the sand return pipe 23 depending from the member 21 centrally in the perforated pipe section 9. The sleeve 22 is exteriorally threaded and similar to the sleeve 16, previously mentioned. The sleeve 22 is threaded in the lower end of the member 21 with its bore registering with the central bore of said member 21. The sand return pipe 23 has 45 its upper end slightly enlarged and threaded on the sleeve 22 as shown clearly in Fig. 2.

It is believed the complete construction of the sand trap or separator may now be understood from the foregoing paragraph 50 taken in connection with the accompanying drawings. It should also be evident to those familiar with this art that as the sucker rod 2 with its valve structure 4 is reciprocated, the fluid from the well will be 55 drawn upwardly through the pipe section or barrel 5, through the perforated pipe section 9, the pipe section 23 then through the pipe sections 7 and 6, by way of the members 21, 14 and 17 and the sleeves 22 and 16 60 and finally through the valve casing 20 into the pump pipe section or barrel 3, so that the fluid may be drawn upwardly by the operation of the sucker rod with its valve structure 4. During this upward travel of the 65 fluid, the sand and other foreign matter is

constantly thrown to the side or inner wall of the members through which the fluid is passing, thereby separating the sand and other foreign matter from the oil or fluid proper. Then as the pump sucker rod 2 and its valve structure 4 are returned or moved downwardly, the separated foreign matter will pass downwardly through the tube 17, through the sleeve 16 and the member 14 into the pipe section 7 of the sand trap or 70 separator. This foreign matter together with all which had been separated from the fluid within the pipe section 7 will drop into the member 21 and pass through the same by way of the sleeve 22 into the sand return 80 pipe 23 to again return to the well. It is also evident that the largest quantity of the sand and other foreign matter will be separated from the fluid while passing through the pipe section 7 of the sand trap 85 or separator. It is also evident that the portion of the sand and other foreign matter will during the upward travel of the fluid be thrown to the inner wall of the perforated pipe section 9 and pass out of the same 90 by way of perforations in the upper portion of the pipe section 9 and then pass out of the perforation in the lower portion of the outer perforated section 13 back into the well casing 1 and return to the well. The 95 quantity of fluid returning with the separated sand and other foreign matter to the well will be small and will not therefore decrease the efficiency of the pump. The separation of the sand and other foreign matter from the fluid before the same reaches the sucker rod valve structure will serve to considerably increase the efficiency of the pump and eliminate the necessity of constantly removing and cleaning or regrinding this valve structure and repairing other parts of the pump structure or emptying sand and other foreign matter from the pump structure, as the separated foreign matter is not permanently trapped or held 100 in the pump structure but permitted to return to the well as rapidly as it is separated from the fluid proper. It is believed that further detailed description of the operation of the pump structure with the inclosed 115 sand trap or separator embodied therein is unnecessary.

While the preferred embodiment of the invention has been shown and described, it is to be understood that minor changes in 120 the details of construction and arrangement of parts may be resorted to within the scope of what is claimed without departing from the spirit of the invention.

What is claimed is:

1. A sand separator for a pump structure comprising the combination with separated section of the pump barrel, of connected pipe sections between the sections of said barrel, a depending frusto-conical member 130

- within said connected pipe sections, a tube 5 extended upwardly from said depending frusto-conical member, a valve mounted on said tube, a funnel member mounted in said connected pipe sections below said depending frusto-conical member, a sand return pipe depending from said funnel member, and perforated pipe sections surrounding said depending sand return pipe.
- 10 2. A sand separator for a pump structure comprising the combination with separated sections of the pump barrel and the inclosing pump casing, of pipe sections connected with one another and with the separated 15 sections of the pump barrel to connect said sections of the pump barrel, an upper inverted frusto-conical member positioned in said connecting pipe sections and having a central passage extending therethrough, a 20 valve mounted on said member, a lower funnel sand return member positioned in said connecting pipe sections, a sand return pipe depending from said lower funnel sand return member, and spaced perforated pipe 25 sections surrounding said depending sand return pipe and having offset perforations.
3. A sand separator for a pump structure comprising the combination with the well casing, the connected pump pipe and barrel sections within said well casing and 30 the pump sucker rod and valve structure within one of the barrel sections, of an upper sand separating member within one of the pipe sections below said sucker rod and valve structure, a lower sand separating 35 member within one of said pipe sections and including a funnel member and sand return pipe depending from said funnel member, means for connecting said sand return pipe with said funnel member, with a central 40 bore communicating with and corresponding with the central bore of the funnel member, and spaced inner and outer perforated pipe sections around said sand return pipe, said 45 perforated pipe sections having series of perforations at their opposite ends and offset from one another.

In testimony whereof, I affix my signature.

SAMUEL W. BATEMAN.
